MERCHANDISING DISPLAY STAND FOR CIGARETTE LIGHTERS OR THE LIKE

Frank H. Stephens, Jr., Atlanta, Ga., assignor to Scripto, Inc., a corporation of Georgia

Filed May 8, 1962, Ser. No. 70,038

Term of patent 14 years

(Cl. D80—9)

Fig. 1

Fig. 2

Fig. 3

Fig. 4

Fig. 5

Fig. 6

FIG. 1 is a perspective view of the merchandising display stand embodying my new design;
FIG. 2 is a side elevational view thereof;
FIG. 3 is a front elevational view thereof;
FIG. 4 is a top plan view thereof;
FIG. 5 is an enlarged scale fragmentary sectional view taken one line 5—5 of FIG. 3; and
FIG. 6 is a rear elevational view of the display stand.

I claim:

The ornamental design for a merchandising display stand for cigarette lighters or the like, as shown.
